(57) CLAIM

The ornamental design for a weightlifting handle, as shown and described.

DESCRIPTION

FIG. 1 is a perspective view of my new design;

FIG. 2 is a top view thereof;

FIG. 3 is a front view thereof;

FIG. 4 is a rear view thereof;

FIG. 5 is a bottom view thereof;

FIG. 6 is a side view thereof;

FIG. 7 is another side view thereof;

FIG. 8 is a perspective view thereof showing an alternate position;

FIG. 9 is a top view thereof showing an alternate position;

FIG. 10 is a front view thereof showing an alternate position;

and,

FIG. 11 is a top view thereof.

The broken line showing of a weightlifting device depicts environment and forms no part of the claim.
